His Attorney

UNITED STATES PATENT OFFICE.

WILLIAM HURST, OF WINNIPEG, MANITOBA, CANADA.

ELECTRICAL RADIATOR-HEATER.

Specification of Letters Patent.

Patented Jan. 6, 1920.

1,327,279.

Application filed January 17, 1918. Serial No. 212,302.

To all whom it may concern:

Be it known that I, WILLIAM HURST, a citizen of the Dominion of Canada, residing at the city of Winnipeg, in the Province of 5 Manitoba, in the Dominion of Canada, have invented certain new and useful Improvements in Electrical Radiator-Heaters, of which the following is a specification.

This invention relates to means for heating 10 the radiators of automobiles in severe weather, and the object of the invention is to provide means easily attachable to automobiles of standard construction whereby the water in the radiators of such cars may 15 be kept at a nonfreezing temperature while the machine is not in use, such means being capable of connection with an ordinary lamp socket such as is usually to be found in any garage, or with any other suitable and convenient source of electrical energy. By the 20 use of this invention the necessity of draining the radiators of automobiles during freezing weather is entirely obviated, and the further difficulty usually experienced in 25 starting a cold engine, overcome.

With these objects in view, the invention consists in the novel combination and arrangement of parts hereinafter first fully described in the following specification and 30 then more particularly pointed out in the appended claims, reference also being had to the drawings forming part hereof, in which similar characters of reference indicate similar parts throughout the different 35 views, and in which—

Figure 1 is a front elevation of an automobile radiator showing the device partially in section, connected therewith.

Fig. 2 is an enlarged side elevation of the 40 device apart from the radiator.

Fig. 3 is a short section of pipe which forms the casing in which the heating element is contained.

Fig. 4 is the elbow and nipple used to 45 connect the casing with the radiator.

Fig. 5 is an elevation of the heating element apart from the rest of the device, a portion of the end being broken away to 50 show the contacts by which it is connected with a lamp cord.

Fig. 6 shows the cap which surrounds the neck of the heating element and closes the end of the casing.

Fig. 7 is the cap which engages the packing 55 gland on the end of the casing cap to

compress the packing in the gland to form a water tight joint around the neck of the heating element.

This invention consists of a casing 1 which may be a short length of pipe of suitable 60 diameter having its ends screw-threaded as at 2 and 3, an elbow 4 engaging the threads 2 and a nipple 5 connecting the elbow 4 with the radiator 6 at the point 7 usually occupied by a tap or pet cock by which the 65 radiator may be drained in freezing weather.

A heating member 8 has an enlarged end 70 disposed within the casing 1 in spaced relation to the walls thereof, and a neck 10 passing out centrally through a cap 11 shaped to engage the threads 3 to close the end of the casing, the cap 11 being formed with a gland 12 on its outer side surrounding the neck 10 of the heating member and 75 shaped to receive a packing 13 of any suitable material, the gland being exteriorly screw-threaded as at 14 to receive a nut 15 adapted to compress the packing in the 80 gland and form a water tight joint around the said neck 10.

The heating element has the contact points 85 arranged in its outer end whereby it may be detachably connected in the usual manner with a cord 17 of good electrical conductivity running to a lamp socket or other source of electrical energy.

The construction of the heating element forms no part of the present invention and it may be of any of the well known formations, but a resistance coil 18 is shown in the enlarged portion of the element in Fig. 1 as a possible means of turning the electric current to account as a heating medium, the contacts 16 being connected with the 95 coil in the usual manner of such constructions.

In Fig. 2 a pet cock 19 is shown tapped into the casing 1 at a point adjacent the cap 11, thus providing for the draining of 100 the radiator through the casing. In Fig. 1 the pet cock 19 is shown connected with the casing 1 by means of a T 20 and nipple 21, a pipe 22 forming a possible connection between the T and the radiator at 105 the top of the latter, by which a circulation of the water through the casing would be insured. However, in practice, through the fact that the heating element is axially disposed in the casing and maintained in the 110

said position by the packing 13 in the gland 12 and spaced from the walls of the casing, the device maintains its own circulation in the casing 1 and the water in the radiator 5 is easily kept at a non-freezing temperature in coldest weather.

From the foregoing description it will be seen that the primary purpose of the invention is to provide means permanently connected with the car radiator and preferably below the same, by which when the car is to be left in the garage, the said means may be instantly connected with a lamp socket and the water in the radiator heated 10 thereby. It is of course obvious that the necessary current might be obtained from sources other than a lamp socket, such for instance as a storage battery forming part of the equipment of the car, in which case 15 the utility of the device would be extended to street use and available at any time or place at which the car might be standing and the engine stopped. It is further obvious that connection with the radiator of 20 an automobile is by no means the only field of usefulness for the device, many other applications of the device will readily occur to persons skilled in the art to which it appertains, as also minor variations and 25 changes in the details of construction of the various parts and the combinations of the same, and I would of course claim as mine all such changes and variations as could be rightfully considered as coming within the 30 spirit of the invention or within the scope of the appended claims.

What I claim is—

1. A device of the kind described comprising an elbow and means to connect the elbow with the water cooling system of an automobile, a horizontal pipe in screw-threaded engagement with the elbow, a detachable cap on the opposite end of the pipe, an electrically energized heating element contained in the pipe in spaced relation to the sides thereof, and having a portion projecting through the cap, and means forming a water tight joint around the projecting portion of the heating element.

2. A device of the kind described comprising a cylinder exteriorly screw-threaded at each end horizontally positioned below the radiator, a reducing elbow on one end of the cylinder, a cap on the other end of the cylinder, a resistance element carrying body 55 contained in the cylinder and having a portion projecting out centrally through the cap, a packing gland on the cap surrounding the projecting portion of the resistance element carrying body, a centrally apertured closure in screw-threaded engagement with the gland coöperating with the cap on the cylinder to maintain the resistance element carrying body in spaced relation to the walls of the cylinder, and wires for connecting the heater with a suitable source of electrical energy adapted for detachable connection with the projecting portion of the resistance element carrying body.

In testimony whereof I affix my signature.

WILLIAM HURST.
